INVENTOR,

Wm. Burnett

UNITED STATES PATENT OFFICE.

WILLIAM BURNETT OF NEW YORK, N. Y., ASSIGNOR TO JOHN B. GRAY, OF SAME PLACE.

RAILWAY-CAR HEATER.

SPECIFICATION forming part of Letters Patent No. 398,816, dated March 5, 1889.

Application filed May 2, 1887. Serial No. 236,814. (No model.)

To all whom it may concern:

Be it known that I, WILLIAM BURNETT, a citizen of the United States, residing at New York, in the county and State of New York, have invented certain new and useful Improvements in Devices for Heating the Cars of Steam-Railways, of which the following is a specification, reference being had to the accompanying drawings.

10 My invention relates to heating devices which employ pipes as a means of conveying to every part of the car the heat transmitted from the generator.

15 The object of my invention is to provide a heating device more manageable and effective than any heretofore devised, and entirely free from danger of fire or explosion.

20 My invention of a railway-car heater, for which my application for Letters Patent was filed March 29, 1887, Serial No. 232,826, consists (as therein stated) in providing within each car separately an arrangement of heating-pipes which presents a continuous and unbroken circuit, through which air, steam, or water, or 25 the like, is impelled by a steam-jet, which not only causes the medium selected to circulate rapidly through the heating-pipes, but by its condensation imparts its heat to the fluid body impelled by it, and indirectly to the interior surface of the pipes through which it is 30 made to circulate.

35 My said invention consists, further, in the arrangement of certain devices to operate in conjunction with the heating-pipes, the same having reference to the employment of the several heat-conveying mediums enumerated, or their equivalents.

40 My present invention consists of an improved arrangement of the heating-pipes, by means of which the steam-jet is made more effective through the introduction of a new operative force which may be made to serve in conjunction with the steam-jet, or separately, as may be desired, which will be hereinafter fully explained. The steam employed is obtained from the locomotive-boiler through 45 mains situated under the several cars, and connected together by suitable hose. From the main so provided a small branch steam-pipe enters each car and connects with the heating device.

Referring to the drawings, Figure 1 is a side

sectional elevation of the heating device, entire and Fig. 2 is a sectional elevation of a modified form of the steam-jet pipe enlarged. 55

The construction of this heating device is as follows: The horizontal pipes A and B extend nearly the entire length of the car, and may be placed against the side wall of the car on either side, and near the floor. The outer ends of 60 these pipes are connected together by a half-turn elbow, C. The vertical pipes D and E are connected to the pipes A and B, respectively, by the quarter-turn elbows F and G, the said vertical pipes being connected together at their lower ends by the half-turn elbow H, the pipes D and E and elbow H forming an inverted siphon having the legs 65 D and E. The plane T T may be taken to represent the platform upon which the device 70 is mounted for attachment to the floor of the car.

R is a relief-valve with discharge-pipe S to limit the pressure within the instrument.

Q is a gage to indicate the internal pressure. 75

I is a steam-jet pipe, the top end of which is situated centrally within the mouth of pipe D. To this jet-pipe the steam is supplied from the steam-main under the car, through pipes J and L and half-turn elbow M, and its 80 flow is regulated by valve K.

P is an air-cock, N a waste-water cock, and O an air and waste-water cock.

The operation is as follows: The circuit pipes containing atmospheric air only, the 85 steam-jet is let on by opening valve K, and a current of intermingled air and steam at once begins to circulate through the heating-pipes, as from the upper end of the jet-pipe through D F A C B G E H to the point of beginning, 90 and so on, making the circuit of the pipes continuous. Water accruing from steam condensation may be permitted to escape as a drip from waste-water cock O, or may be made to pass through a steam-trap. When 95 steam alone is employed as a circulating medium, the manipulation is the same as for air and steam commingled, except that before starting the steam-jet the air-cock O should be opened to permit the air to escape from the 100 heating-pipes, as the steam from the jet enters to take its place. When hot water is to be employed as a circulating medium, the water may be obtained by steam condensation

in the heating-pipes, and in this case none of the water of condensation will be discharged until the pipes are entirely full, when any further accumulation will pass off through relief-valve R, operating automatically. The water will be rapidly circulated through the heating-pipes and kept at a suitable temperature by the impelling steam-jet; but the temperature of the pipes may be modified to any degree by closing the steam-induction valve K more or less, as may be found necessary.

The most important part of my present invention consists in arranging a portion of the pipe-circuit in the form of an inverted siphon, as shown at D E H, by which means I am enabled to employ not only the mechanical force of the steam-jet in producing and maintaining the water circulation, but to take advantage of the presence in the column of steam supplied by the jet, which reduces the weight of the column and assists in the production of a rapid circulation of the water through the heating-pipes by reason of the preponderance of the opposed solid water column in pipe E. While the operation of this auxiliary force is necessarily involved in the use of a steam-jet arranged substantially as herein described, its greatest efficacy is developed when employed separately from the steam-jet. I therefore sometimes employ a jet-pipe constructed like that shown at Fig. 2, in which the

central vertical jet-opening is dispensed with, and a number of small lateral openings, a, substituted, through which the steam is permitted to flow out and commingle with the water of column D. The steam is introduced at the lower end of the pipe, and, passing upward by its ascensive power, lightens the water column in pipe D, so that the opposed water column in pipe E will have preponderance, and thereby cause continual displacement of the lighter column.

Having thus fully described my invention, what I claim, and desire to secure by Letters Patent, is—

1. The combination, with a radiator-pipe having a depending loop, the two forming a complete circuit of pipes for a heating medium, of a jet-pipe extending within the loop, and a suitably-governed valve on the circuit, substantially as described.

2. The combination, with a radiator-pipe having a depending loop, the two forming a complete circuit of pipes for a heating medium, of a jet-pipe extending within the loop, having a closed end and side perforations, and a suitably-governed valve on the circuit, substantially as described.

WILLIAM BURNETT.
